(57) **CLAIM**

The ornamental design for slipper, as shown and described.

DESCRIPTION

FIG. 1 is a front perspective view of the slipper of the present invention showing my new design;

FIG. 2 is front side elevational view thereof;

FIG. 3 is back side elevational view thereof;

FIG. 4 is a side elevational view thereof;

FIG. 5 is another side elevational view thereof;

FIG. 6 is a top plan view thereof; and,

FIG. 7 is a bottom plan view thereof.

The broken lines on the vamp, bottom, heel and along the opening of the slipper represent unclaimed subject matter and form no part of the claim.

1 Claim, 6 Drawing Sheets
